UNITED STATES PATENT OFFICE

122,913

DESIGN FOR A POWER SAW

Laurence Franklin Atwood, Los Angeles County,
Calif.

Application November 13, 1939, Serial No. 88,213

Term of patent 14 years

To all whom it may concern:

Be it known that I, Laurence Franklin Atwood, a citizen of the United States, residing in the city of Pasadena, county of Los Angeles, and State of California, have invented a new, original, and ornamental Design for a Power Saw, of which the following is a specification, reference being had to the accompanying drawings, forming part thereof.

Fig. 1 is a side elevational view of a power saw illustrating my new design. Fig. 2 is a similar view of the other side thereof. Fig. 3 is a front end view thereof. Fig. 4 is a perspective view thereof on an enlarged scale.

I claim:

The ornamental design for a power saw, as shown.

LAURENCE FRANKLIN ATWOOD.
